CLAIM

The ornamental design for a set-top box, as shown and described.

DESCRIPTION

FIG. 1 is a perspective view of a set-top box as viewed from the front, showing our new design;

FIG. 2 is a top plan view thereof;

FIG. 3 is a front elevational view thereof;

FIG. 4 is a bottom plan view thereof;

FIG. 5 is a left side elevational view thereof; and,

FIG. 6 is a right side elevational view thereof.

The broken lines are for illustrative purposes only and form no part of the claimed design.
